Primary Examiner — Brian N Vinson(74) Attorney, Agent, or Firm — QuickPatents; Kevin Prince(57) CLAIM

I claim the ornamental design for an ice chest and fishing pole holder with universal attachments, as shown and described.

DESCRIPTION

FIG. 1 is a perspective view of an ice chest and fishing pole holder with universal attachments, showing my new design; FIG. 2 is a front elevational view thereof; FIG. 3 is a rear elevational view thereof; FIG. 4 is a right-side elevational view thereof, the left-side elevational view being a mirror image thereof; FIG. 5 is a top plan view thereof; and, FIG. 6 is a bottom plan view thereof. The broken lines showing a truck in FIG. 1 depict environmental matter and form no part of the claimed design.
